UNITED STATES PATENT OFFICE.

NILS FREDRIKSSON, OF STOCKHOLM, SWEDEN.

INTERNAL-COMBUSTION ENGINE.

1,334,951.

Specification of Letters Patent.

Patented Mar. 30, 1920.

Application filed August 20, 1919. Serial No. 318,781.

To all whom it may concern:

Be it known that I, NILS FREDRIKSSON, a subject of the King of Sweden, residing at Stockholm, in the Kingdom of Sweden, have invented a new and useful Improvement in Internal-Combustion Engines, of which the following is a specification.

The present invention relates to an improvement in internal combustion engines of the type which are provided in the ordinary manner with a cooling device for the circulating water, a pump for effecting the circulation of the water, a fan for producing an air current for cooling the water, and a starting crank for starting the engine.

The improvement consists principally in this that the circulating pump, the fan, and the starting crank are combined with the cooling device in such manner as to form together with the said device a combined apparatus which may be connected with the engine. In this manner a considerable saving of space and a greater simplicity of construction as well as a better possibility of connecting in suitable manner the said devices, which are combined into a unit, with engines of any desired type is obtained, than if the devices are mounted each by itself as heretofore practised. For this reason the device is especially adapted to be used on tractors and similar motor cars, where the available space is small and it is important to obtain a simple and reliable construction.

An embodiment of the invention is shown in the accompanying drawing which shows a vertical section of the apparatus.

Referring to the drawing 1 denotes the motor engine and 2 the cooling device, which may be of any suitable construction. The circulating pump 3, which is suitably a centrifugal or other rotary pump, is attached directly to one side of the casing of the cooling device. The shaft 4 of the pump projects beyond its bearings, and the end of said shaft directed toward the motor supports a jaw clutch 5, a gear wheel or other means for effecting a driving connection between said shaft and the engine shaft. The other end of the pump shaft projects into the lower portion of the casing of the cooling device and supports a fan wheel 6 of any suitable construction, which fan wheel serves to produce an air current through the cooling device for cooling the water. A shaft 7 is mounted in alinement

with the shaft of the pump and the fan, said shaft 7 being journaled in a bearing 8 rigidly secured by means of arms 9 to the side of the casing of the cooling device opposite the side to which the pump 3 is secured. Said shaft 7 supports at its outer end the starting crank 10 and at its inner end a jaw clutch member 11, said shaft 7 being movable axially so that the jaw member 11 may be brought into engagement with a corresponding jaw clutch member on the hub of the fan wheel 6. Finally, there is provided a coil spring 12 around the shaft 7 which spring serves to maintain the jaw member 11 normally out of engagement with the fan wheel.

The starting of the engine is effected in the usual manner when the jaw clutch member 11 has been moved into engagement with the corresponding member on the hub of the fan wheel, the starting movement being thus transmitted to the engine shaft through the shaft 4 and the clutch 5. The jaws on the clutch member 11 as well as on the fan wheel hub are oblique in the ordinary manner, so that the starting crank is automatically disengaged when the engine is started.

It will be understood from the above description and from the drawing that the circulating pump, the fan and the starting crank form together with the cooling device a unit, and the combination is so designed that the entire apparatus requires the least possible space. It will be understood, however, that the combination of the various devices shown in the drawing may be varied in several respects without departing from the principle of the invention.

I claim:

1. The combination with an internal combustion engine of an apparatus comprising a cooling device, a circulating pump, a fan, and a starting crank, combined into a unit provided with means for being connected to the engine.

2. The combination with an internal combustion engine of an apparatus comprising a cooling device, having a casing, a fan mounted within said casing, a circulating pump mounted on one side of said casing, and a starting crank journaled on the other side of said casing, said cooling device, fan, pump, and crank being combined into a unit provided with means for being connected to the engine.

110

3. The combination with an internal combustion engine of an apparatus comprising a cooling device having a casing, a fan mounted within said casing, a circulating pump mounted on the outside of said casing, a common shaft for said fan and said pump having clutch members at both ends, a sec-

ond shaft journaled in said casing in alignment with the first named shaft and provided with a clutch member on one end, and a starting crank on said second shaft, said cooling device, fan, pump, shafts, and crank being combined into a unit.

NILS FREDRIKSSON.
